UNITED STATES PATENT OFFICE.

GEORGE OHL, OF MERIDEN, CONNECTICUT, ASSIGNOR TO INTERNATIONAL SILVER CO.,
OF MERIDEN, CONNECTICUT, A CORPORATION OF NEW JERSEY.

DESIGN FOR A NAPKIN-HOLDER.

53,603.

Specification for Design.

Patented July 15, 1919.

Application filed March 12, 1919. Serial No. 282,219. Term of patent 7 years.

To all whom it may concern:

Be it known that I, GEORGE OHL, a citizen of the United States, residing at Meriden, in the county of New Haven and State of Connecticut, have invented a new, original, and ornamental Design for a Napkin-Holder, of which the following is a specification, reference being had to the accompanying drawing, forming part thereof.

Fig. 2 is a side view of the same.

Fig. 3 is a sectional view on the line 3—3 of Fig. 1.

I claim:

The ornamental design for a napkin holder, as shown.

GEORGE OHL.

Witnesses:

HARRY E. EWERS,
ARTHUR C. KING.
